UNITED STATES PATENT OFFICE.

EMIL BOMMER, OF BROOKLYN, NEW YORK.

DOOR-CHECKING HINGE.

1,241,082.

Specification of Letters Patent. Patented Sept. 25, 1917.

Application filed May 13, 1914. Serial No. 838,328.

To all whom it may concern:

Be it known that I, EMIL BOMMER, a citizen of the United States, and a resident of New York, in the borough of Brooklyn, county of Kings, and State of New York, have invented certain new and useful Improvements in Door-Checking Hinges, of which the following is a specification.

This invention relates to door-checking hinges, and more particularly to that type in the operation of which a checking liquid is used, when the parts are moved relatively to each other. The object of the invention is to provide certain improvements in door-checking hinges which tend to simplify the construction, increase the efficiency and improve the appearance thereof, and the salient feature of the invention consists in forcing a checking liquid from the interior of one barrel to the interior of the other barrel, through a web or connecting member connecting the barrels, and to so regulate the flow of the checking liquid that an efficient checking action results.

This improved door-checking hinge is usually applied to the door in the same manner that a double-acting or a single-acting spring butt-hinge is applied, namely, between the door and its frame, and has the general appearance of a double-acting spring butt-hinge, or of a single-acting spring butt-hinge, as the case may be, or, in the case of a hinge having surface flanges it may be fastened to the surfaces of the door, and the adjacent door-casing respectively, but in either case it obviates the inelegant and cumbersome appearance of the door-checks now commonly used at one or the other side of the top of the door or door-casing, and the use of the more or less unsightly jointed arm. A further advantage of this improved door-checking hinge is that it can be provided with a self-contained spring or springs for automatically closing the door, or without the same as may be preferred, and can also be applied with great facility to swinging doors, so as to operate in connection with the well known non-checking types of double-acting spring-hinges which automatically restore the door to closed position after being opened, while

the concurrent use of the improved checking-hinge with the spring-hinge prevents the sometimes dangerous quick closing and also the to-and-fro movement or flip-flapping in swinging doors, before they come to rest in their closed position.

The invention is contained in the embodiments shown in the accompanying drawing and will be more fully described hereinafter and finally pointed out in the claims.

In the accompanying drawing,

Figure 1 is a front-view of my improved door-checking hinge as applied to a double-acting hinge, 65

Fig. 2 is an enlarged vertical longitudinal section of the same, with several of the parts in elevation,

25 Fig. 22 is a section taken on line 22—22 of Fig. 21, and

Fig. 23 is a front-view of the structure shown in Fig. 21, with the leaves in open position ready for application to the door and door-casing.

30 Similar characters of reference indicate corresponding parts throughout the various figures of the drawing.

Referring to the drawings, the invention is applicable and is herein described in detail as applied to and embodied in a double-acting door-checking hinge, the changing of a double-acting door-checking hinge to a single-acting door-checking hinge, a double-acting door-checking hinge with self-contained spring, a double-acting door-checking hinge with link connection, and a single-acting door-checking hinge without spring, and a single-acting door-checking hinge with spring, each of which will now be discussed under these various headings.

Double-acting door-checking hinge.

Referring to the drawings, and more particularly to Fig. 1, the double-acting door-checking hinge there shown consists of a connecting-member or web 10 and barrels 11, 12. Movable in respect to the barrels 11 and 12 are the leaves 13 and 15, the leaf 13 having ears 40 and 40^a, and openings 55 14 for screws to pass therethrough to fasten the leaf 13 to the door or to the door-casing, as the case may be, and the leaf 15 having ears 43 and 43^a, and openings 60 16 to permit the passage of screws therethrough to fasten the leaf 15 to the door-casing or door, as the case may be. Ball-tips or other shaped tips 17 and 18, 19 and 20 may or may not be provided as preferred. The parts described resemble in appearance, a double-65 acting spring-hinge, and when such a

double-acting door-checking hinge is applied to a door it has the elegant appearance of such a hinge, in contrast with the overhead door-checks, which are generally considered to be comparatively inelegant and 70 cumbersome in appearance.

Referring more particularly to Fig. 2, the web 10 has a horizontal checking-liquid channel 25 therein, which has one end 26 communicating with the interior of the barrel 11, and has the other end 27 communicating with the interior of the barrel 12. Both the barrels 11 and 12 are hollow, and each barrel has its upper end open, while the lower ends of the barrels are closed by 80 the material of the web being extended to form a closed bottom, as shown in the lower part of Fig. 2.

The closed bottoms of the barrels 11 and 12 are provided at their lower or outer 85 ends with downwardly-projecting studs or pivots 44 and 45 oscillating in corresponding circular sockets of the lower ears 40^a and 43^a of the leaves 13 and 15 respectively. Ball-tips or other shaped tips 19 and 20 engage the ends of pins 44^a and 45^a, which are fastened to the lower ears 40^a and 43^a in any convenient manner.

Within each of the barrels 11 and 12 is a vertical shaft 28 which is made to oscillate when the door-check is operated. The shaft 28 in the barrel 11 is, preferably, in every respect a counterpart of the shaft 28 in the barrel 12. The shaft 28 has at its upper end collars 30 and 32, preferably made 100 integral therewith, and an annular cut-out portion or recess 29 between said collars, as clearly shown in Fig. 4, said cut-out portion or recess 29 enabling a suitable packing material 29^a to be interposed between 105 the collars 30 and 32 and the contiguous wall of the barrel. This is clearly shown in Fig. 3, and lamp-wick or other suitable packing material adapted to prevent the exudation or leakage of the checking liquid 110 in upward direction when the door-check is operated, may be provided. The diameter of the collars 30 and 32 is finished to a close working fit for oscillating within the interior wall of the barrels. Above the upper collars 32 an enlarged upper collar 33, also preferably made integral with the shaft 28 and adapted to extend over the upper edge of the barrels so as to be seated thereon, is arranged. Below the collars 30, the shaft 28 120 is provided with a wing 48 of practically segmental cross-section, and preferably made integral with the shaft 28, said wing having faces 46 and 47 which are preferably radial with the center of the shaft 28. The 125 wing 48 extends downwardly from the collars 30 to the bottom of the barrel 11, the rounded back 49 of the wing 48 being concentric with the shaft 28 and being finished, like the collars 30 and 32, to a working fit 130

for oscillating in the interior wall of the barrel 11. The lower end of the wing 48 is cut out preferably, as shown at 53, and provided with an extending finger-portion 50, which has an opening 51 registering with the ends of the channel 25 when the door-check is in closed position, as shown in Fig. 5. The shaft 28 is also provided with a downwardly-extending stud or pivot-end 52, which is pivoted in a circular socket 54 in the closed bottom of the barrel 11.

Within the interior of the barrels 11 and 12 and rigidly secured thereto by screws 55 or other means or cast integral with the barrels 11 and 12, is an obstructing wall or baffle 56 which has faces 57 and 58 which are preferably radial to the center of the shaft 28 so as to aline with the faces 46 and 47 of the wing 48. The inner surface 20 of the obstructing wall or baffle 56, adjacent to the shaft 28, is concentric with and finished to a working fit with the shaft 28.

The enlarged upper collar 33 of the shaft 28 is provided with a socket 36 which extends downward and preferably into the collar 32, and also preferably has a perforation 34 passing diametrically therethrough. Between the enlarged upper collar 33 of the shaft 28 and the ear 40, a spacing washer 38, having a central perforation, may be arranged, said spacing washer 38 being inserted merely for convenience in assembling the parts of the door-checking hinge. The ear 40 of the leaf 13 has a perforation 42 passing diametrically therethrough. A vertical pin-shaft 37 having diametrical perforations 35 and 39, which register with the perforations 34 of the collar 33 and the perforation 42 of the ear 40, extends downwardly through the ear 40, spacing washer 38 and into the socket 36 of the collar 33. When the perforations respectively of the pin-shaft 37, ear 40 and collar 33 are in register, pins 35^a and 41 are inserted therein 45 and one method of securing a rigid connection or locking of the leaf 13 with the oscillating shaft 28 to simultaneous movement is thereby disclosed. By this connection, the movement of the leaf 13 causes the movement of the oscillating shaft 28 in the barrel 11. The leaf 15 is connected in like manner to the other oscillating shaft 28. Ball-tips or other shaped tips may, if desired, be attached, for instance, to screw-threaded projecting ends 37^a of the pin-shaft 37.

A suitable controlling-screw 60, shown in Fig. 2, or a similar device, may be inserted into a perforation 61 of the lower edge of the web, which screw is preferably provided with a packing to prevent escape of liquid, as shown at 62. This screw may be located at any suitable point of the connecting-plate or web 10, provided it shall intersect the channel 25, for the purpose of varying the 65 cross-sectional area of the said channel 25,

and thereby permitting a further control of the volume of flow of the checking-liquid from one barrel to the other barrel, if found necessary in the case, for instance, of specially heavy doors or in case of thinning 70 of the checking-liquid in very hot weather, and at the same time also thereby further controlling the checking speed of the door-checking hinge, and finally also thereby providing a means for increasing or diminishing, or for draining or renewing the supply of checking-liquid, as may prove to be desirable.

The parts co-operating with and moving within the barrels 12 of the different embodiments simultaneously with the leaf 15, are exactly the same in construction as hereinbefore described for barrel 11 and leaf 13, as will be clearly seen by a comparison of the right-hand side with the left-hand side 85 of the view shown in Figs. 2, 5 and 6.

This door-checking hinge can be produced without spring-power for closing the door; the embodiment shown in Figs. 1 to 6 is intended only for use on doors which are automatically closed by one or more additional double-acting spring-hinges, or by some similar door-closing device, and is designed to check the momentum of such doors when closing, and to prevent them from swinging 90 to and fro before coming to rest at their closed position, which action is termed "flip-flapping."

Referring more particularly to Fig. 5, in which a horizontal section is shown, it 100 will be noted that the leaves 13 and 15 are parallel with and substantially contact with the web 10 of the door-checking hinge, as is usual in double-acting spring-hinges. When the leaves 13 and 15 are in this position, the extending finger-portion 50 of the shaft 28 is in proximity to the surface 57 of the obstructing wall or baffle 56 of the barrel 11, and it then has its opening 51 in register with the opening 26 of the channel 25, and 110 similarly the other extending finger-portion 50 of the other shaft 28 in the barrel 12 has then also its opening 51 in register with the opening 27 of the channel 25. When the parts are in this position, the checking 115 liquid which is placed within the channel 25 and the barrels 11 and 12, between the face 57 of the baffle 56 and face 47 of the wing 48, will readily find its own level in the two barrels, and by reason thereof approximately 120 equal portions of the liquid will collect in each barrel, and the channel 25 connecting the barrels 11 and 12 is then unobstructed.

Referring now more particularly to Fig. 6, the leaf 13 of the barrel 11 is in a position 125 corresponding to the open position of the door, namely, in a position at right angles to the position of the same part shown in Fig. 5. It will be noted that by the movement of the leaf 13, the shaft 28 is correspondingly 130

moved and the extending finger-portion 50 of the wing 48, together with its opening 51, has now passed over and beyond the channel 25 and that the space between the face 57 of the baffle 56 and the face 47 of the wing 48 is thereby greatly increased. This act of opening the door will cause the greater portion of the checking-liquid in the barrel at the other side of the hinge to flow through the channel 25 into the barrel 11. The act of opening the door creates a suction proportionate in energy to the speed or force with which the door is opened, and correspondingly accelerates the movement of the checking-liquid into the greatly increased space in the barrel 11.

When, however, the door closes under the spring-pressure of its independent door-closing device, or for instance, under the pressure of its self-contained door-closing spring, if any, the increased volume of checking liquid in the barrel 11 is forced thereby to return again through the channel 25 to the other barrel 12 at the other 25 side of the hinge, at a speed and pressure proportionate to the spring-power of the said door-closing device and the speed of flow of the checking-liquid through the channel 25. This takes place until the extending finger-portion 50 of the wing 48 extends over and closes the opening 26 of the channel 25, whereby an additional and more or less positive check is given at this point against the further closing of the door by reason of the fact that the flow of the checking-liquid is prevented by the stopping of the channel 25 by the end portion of the finger 50. This, however, in practice is soon relieved, probably by a certain leakage of the checking-liquid under pressure between the parts, or by the movement of the liquid upwardly probably against the more or less compressed air in the barrel. After this secondary checking action is overcome, then the registering of the opening 51 with the opening 26 of channel 25 gradually takes place by the continued movement of the shaft 28 and finger 50 under the pressure exerted by the additional independent door-closing device or by the self-contained 40 springs, if any, whereupon the liquid passes through the channel 25, and the liquid may then again equalize in the barrels 11 and 12 and channel 25. By the use of this checking action, the door closes silently, and in the case of a swinging door without any to-and-fro movement, and this relief of the checking-action at or near the closing position of the door, leaves the independent door-closing device or the self-contained 45 springs free to latch the door or hold it in closed position, as the case may require. It is clear that on the movement of the leaf 15 a like sequence of action takes place.

60 Through the coöperation of the parts and

the reciprocatory movement of the checking liquid from one barrel or container to the other barrel or container through the connecting-channel 25 of the web or connecting member 10, as the door is opened to one side or the other, a very efficient door-checking hinge is produced, which is of great simplicity and durability in all its parts and which has an elegant appearance.

Changing a double-acting door-checking hinge to a single-acting door-checking hinge.

It is clear that my invention may find application to other embodiments utilizing the fundamental principle, and thus is applicable to a single-acting hinge either in a left-hand or right-hand direction. This becomes apparent, for instance, when one of the leaves in the embodiments so far described is fastened to the web with screws 99 or other means, whereby, on the operation of the door, the equivalent of a single-acting door-check would result.

Double-acting door-checking hinge with self-contained spring.

To show that the invention, as embodied in this door-checking hinge, can also be arranged to coöperate with self-contained springs for automatically closing the door, the embodiments shown in Figs. 10 to 12 are shown, in which a pair of these double-acting spring-hinges can be used without any additional door-closing device or spring-hinge.

In Figs. 10, 11 and 12 a combined double-acting door-check with a spring-hinge is shown, in which the door-checking portion is preferably arranged uppermost, and the hinge-portion is preferably arranged lowermost. In this embodiment, the leaf 70 has three ears 71, 72 and 73, and the leaf 74 has three ears 75, 76 and 77. The leaves 70 and 74 have the usual screw-openings 78^a for fastening purposes. Between the ears 71 and 72, the barrel 78, which is preferably made integral with the web 85 of the door-checking portion, is seated, said barrel 78 inclosing the oscillating shaft 28, with its finger 50, wing 45, packing 29^a, and collars 30, 32 and 33. The collar 33 is keyed to the ear 70 by the vertical pin 37 and horizontal pins 39 and 35^a. The washer 38 is interposed between the ear 70 and collar 33. All these parts are arranged in the same manner and have the same sequence of action as shown in the embodiment illustrated in Figs. 1 to 6. A similar mechanism is arranged within the barrel 80 of the door-checking portion which barrel is also preferably made integral with the web 85. Tips 17, 18, 19 and 20 may also be suitably applied.

Between the ears 72 and 73, a preferably

separate barrel 81 of the spring-hinge portion is seated, and between the corresponding ears 76 and 77 a similar preferably separate barrel 82 is seated. The barrels 81 and 82, as also the barrels 80 and 78, are connected with a web 85 common to all the barrels. This web 85 has a channel 25 for the checking-liquid therein, which channel 25 connects the barrels 78 and 80, and 10 through which the checking-liquid operates in the manner described in connection with the embodiments particularly described heretofore and shown in Figs. 1 to 6. A governing device consisting in this case preferably 15 of a rotatable plug 87 with a channel 88 is interposed in the path of the channel 25, and the movement of the plug in respect to the channel causes the channel 25 to be more or less opened or closed, depending upon 20 whether the channel 88 is desired to be incomplete or partial or not in registration with the checking-liquid-channel 25. This is clearly shown in Fig. 12, and the plug 87 may be readily operated by the preferably 25 slotted head 87^a, having a slot 87^b.

Referring to the spring-hinge portion in Fig. 10, the pintle 90 is preferably screw-threaded at both ends, and the upper end 91 engages corresponding screw-threads in the ear 72, while the lower end 92 extends through and beyond the ear 73 and preferably engages a screw-threaded socket in the tip 19. An adjustable spring-holder 93 with adjusting-openings 94, is engaged by 30 the coil-spring 95; the other end of the coil-spring 95 engages the fixed spring-holder 96. This fixed spring-holder 96 is secured to the barrel by a projecting pin or plug 97, and when the spring is set to tension, this 35 pin or plug abuts against the web 85 under the recoil of the spring. The adjustable spring-holder is set to tension by the aid of a lever or piece of wire and the tension pin is then inserted and which is forced by the 40 recoil of the spring to set against the back edge of the flange 70, as is usual in spring-hinges.

By this combined door checking hinge and spring-hinge, a very efficient device is 45 produced which has the advantages of both members, all arranged in a very compact manner, the spring serving to close the door while the door-checking device serves to control the movement of the door by checking its movement and preventing the to-and-fro movement, or flip-flapping at the closed position of the door. This advantageous combination is brought about by the special structure shown and described.

50 It will be clearly understood from the foregoing descriptions of both the double-acting door-checking hinge and of the combined double-acting door-checking spring-hinge, that close registration of the channel 55 25 with the opening 51 of the finger 50 is

desirable for the efficient operation of the checking action of the double-acting type of hinge.

Link connection of a double-acting door-checking hinge.

70

Referring now more particularly to Figs. 13, 14, 15, 16, and 17, it is well known that the leaves of a double-acting spring-hinge invariably tend to separate from the web 75 connecting the barrels when supporting the weight of a heavy door. Unless the independent door-closing device or the self-contained door-closing springs are of amply-sufficient-power not alone to close the door, 80 but also to hold the leaves closed against the connecting-web of the barrels under all conditions and circumstances, it becomes necessary to provide in addition thereto a reliable and positive means for preventing the separation of the leaves from the connecting-web 85 of the barrels, and to compel the leaves to remain parallel with the web when the door approaches its closed position or position of registration of the opening 51 of finger 50 90 with the checking-liquid channel 25.

In Figs. 13 to 17, embodiments containing these co-operating parts are shown, in which Fig. 13 shows a combined door-check and spring-hinge provided with extension-brackets and a connecting-strap, the object of the extension-brackets and connecting-strap being to prevent the sagging of the door, and thereby insure a proper registration of the opening in the extending finger 100 50 and the checking-liquid channel 25. Referring to Fig. 13, the leaf 100 is provided with an ear 101, a second ear 102, and a third ear 103, and the leaf 104 is provided with an ear 105, a second ear 106, and a third ear 107. Barrels 108 and 109, and 110 and 111 are suitably supported and arranged between the ears in a manner similar to the embodiment of Fig. 10. In the upper portion of the embodiment shown in Fig. 110 13, the door-checking parts, consisting of the shaft 28, collars 30, 32 and 33, with finger 50, are arranged and are of a construction like the corresponding parts in Figs. 1 to 6; for instance, the collar 33 is 115 keyed to the vertical pin 112, and this vertical pin is locked to the ear 105 by the horizontal pin 113. The spring-hinge portion has a pintle 115, an adjustable spring-holder 116, a fixed spring-holder 117, a coil-spring 120 118, arranged in a manner similar to that described in connection with Fig. 10. To prevent, however, the sagging of the door, as stated, the leaf 100 is provided with an extension-bracket 120, and the leaf 104 is 125 provided with an extension-bracket 121, this extension-bracket 121 being in a position directly over the barrel 108 and ear 101, and this bracket 121 being free from the ear 101 so as to be movable away therefrom. To 130

the extension-bracket 120 and the extension-bracket 121, a strap or link 123 is suitably hinged or pivoted, and above the strap or link 123, tips 124 and 125 may be applied. 15 The distance between centers of the openings of the strap 123 is equal to the distance between the centers of the two barrels 108 and 110, so that the device shown in Fig. 13 may be moved into either position, 20 as shown in Figs. 15 and 16, and as is more fully described in my Patent No. 12,236, re-issued to me on June 28, 1904. In Fig. 15 one position of the parts is shown, where the door 127 is at right angles to the jamb 128 when 25 in one position, while in Fig. 16 is shown the door 127 at right angles to the jamb 128 when in another position. It will be clearly seen from an examination of Figs. 13, 14, 15 and 16, that the distance between 30 centers of the openings of the strap 123 is equal to the distance between the center of the barrel 108 and the center of the opening of the bracket 120 on the one hand, and the distance between the center of the barrel 108 and the center of the barrel 110 on the other hand, which said distances are equal in length, so that the door is free to move from the position shown in Fig. 15 to the position shown in Fig. 16, or also to the position shown in Fig. 14.

In order to clearly bring out the co-operation of the extension-brackets and connecting link or strap with my improved door-checking hinge, and as it is important in the 35 use of my door-checking hinge that the channel in the finger 50 be at certain times in close registration with the ends of the checking-liquid channel, the structure shown in Fig. 17 is shown. In this embodiment the 40 shaft 28 again has its finger 50 co-operating with the channel 25, and the collars 30, 32 and 33, with packing 29^a, are all integral and are keyed to the vertical pin 130, which in turn is keyed to the ear 131 by the horizontal pin 132. These parts are all of the 45 structure shown clearly, for instance, in Fig. 2, and operate in the same manner; but in the embodiment shown in Figs. 17 and 18 the leaf 135 is provided with an extension-bracket 136, which is free of the ear 131 and movable freely in respect thereto, while the other leaf 137 is provided with an extension-bracket 138, which is also free of the ear 139 and free to move in respect thereto. The 50 extension-brackets 136 and 138 are hinged or pivoted with each other by a strap or link 139^a, the distance between centers of the openings of this strap or link again being equal to the distance between the centers of 55 the two barrels, indicated in Fig. 17 by 140 and 141. Suitable tips 142 and 143 may be readily applied by having their screw-threaded sockets engage with the screw-threaded portions 145 of pins 130.

60 In Fig. 18 the jamb 128 and the door 127

are again shown in partial section to illustrate the application of the structure to the door. Reference is here again made to the patent referred to, Reissue No. 12,236 of June 28, 1904. It is quite clear that though 70 the embodiments of Figs. 13 to 17 show the extension-brackets and the links or straps at the upper part of the leaves, similar extension-brackets and straps or links may be arranged also at the lower part of the leaves, 75 or they may be either at the top or at the bottom as desired. By this arrangement, when the leaf only of the double-acting door-checking hinge moves in unison with the door, the link or strap also moves therewith; 80 and when the other leaf, together with the web, moves with the door, the link or strap remains at the door-casing; thereby in each case locking each leaf alternately to the barrel as the weight of the door is shifted from 85 the axis of one barrel to the axis of the other barrel, when the door is made to oscillate from side to side, whereby invariably the close registration of the checking-liquid channel with the opening 51 is effected. 90

Single-acting door-checking hinge.

It will have been noticed that if in the embodiment shown in Fig. 13, for instance, as 95 also in the embodiment shown in Fig. 10, and also that in Figs. 2, 10 and 11 one of the leaves is secured to the web by the fastening screws 99, only one of the barrels with the door-checking members, or spring-hinge members, or both, as the case may be, is free 100 to move, and the action that will then result is substantially that of a single-acting hinge, rather than that of a double-acting hinge. In order to make the invention herein disclosed applicable to a single-acting hinge 105 without the necessity of fastening these members together, the embodiment shown in Fig. 19 is shown, in which is embodied the underlying principle of my invention. In this embodiment the leaf 140 is provided 110 with a main barrel 141 in which is arranged the shaft 28 with the finger 50 and the collar 30, packing 29^a, collar 32 and enlarged collar 33 all keyed to the vertical pin 37 by the horizontal pins 39 and 35. The upper portion 115 of this pin is screw-threaded to engage a screw-threaded socket 142 of the tip 143. The lower part of the barrel 141 is closed by the member 145 and is provided with a screw-threaded socket 146 adapted to be engaged by a screw-threaded end of a vertical pin 147, the other screw-threaded end of which may engage a screw-threaded socket 149 of the tip 150. All these parts are substantially of the same construction and operate 120 in the same manner and contain the same underlying principle as the corresponding parts in the embodiments shown in Figs. 1 to 6. Instead, however, of providing a complete duplicate of these parts, an auxiliary 125

barrel is provided, preferably on the rear surface of the leaf 140 and alongside of the barrel 141, so that it may be hidden in a suitable mortise of the door or door-casing. This auxiliary barrel 151 has a closed bottom 152 and an open top 153, which is engaged by a screw-threaded plug 154. This barrel 151 is so arranged in respect to the barrel 141 that it may readily coöperate therewith, and in the embodiment shown in Fig. 19, the connecting member 155, which conforms substantially to the web 10 of the embodiment shown in Fig. 2, for instance, is arranged. The lower part of this connecting member 155, or web, if it is desired to be so called, is provided with a checking-liquid connecting-channel 25 which brings about communication between the interior of the barrel 141 with the interior of the barrel 151. A suitable screw-plug 156, substantially like the screw-plug 60 of Fig. 2, may be provided for the same purposes as the screw-plug 60. The operation of the shaft 28, with its wing 45 and finger 50, is exactly like that already described, and it forces into the auxiliary barrel 151 or sucks out therefrom by means of the channel 25, the checking-liquid and in all respects operates in the same way as the embodiments in Figs. 1 to 6, with the exception only, of course, that the embodiment of Fig. 10 is only capable of operating in one direction.

The operation of the embodiments of Figs. 21, 22 and 23, is substantially like that of Fig. 19, and more particularly also like the embodiment in Fig. 10, being, however, only of a single-acting character, whereas the embodiment in Fig. 10 is double-acting.

In the embodiment shown in Fig. 21, the door-checking portion embodies the same elements as that of Fig. 19, and the lower portion again has the adjustable spring-holder 93, the pintle 90, the barrel 81, the coil spring 95, the fixed spring-holder 96, the ears 72 and 73, and the tip 19, and in Fig. 23 the leaf 140^a has openings 162 for the fastening screws, as also the leaf 140^b has openings 160 for the fastening screws, clearly shown. It is clear, however, that the spring-hinge portion may be arranged on the upper part and the door-checking portion at the lower part, or that other suitable combinations may be made in the form of placing one spring-hinge portion between two door-checking portions, or one door-checking portion may be placed between two spring-hinge portions.

I have shown several embodiments of my invention, but changes may be made therein without departing from the spirit of the invention as defined in the appended claims.

I claim:

1. A door-checking hinge, comprising barrels, a connecting member for the bar-

rels having a channel communicating with the interior of each of the barrels for equalizing the checking liquid in the barrels and channel, and means causing the flow of the checking liquid from one barrel to the other, 70 through the channel in the connecting member.

2. A door-checking hinge, comprising barrels, a web for the barrels having a channel communicating with the interior of each 75 of the barrels for equalizing the checking liquid in the barrels and channel, and means for causing the flow of the checking liquid into either of the barrels and forcing the checking liquid, caused to flow into one of 80 the barrels, back again through the channel into the other of the barrels.

3. A door-checking hinge, comprising barrels, a web for the barrels having a channel communicating with the interior of each 85 of the barrels for equalizing the checking liquid in the barrels and channel, and an oscillating shaft in each barrel having means thereon for causing the flow of the checking liquid into either of the barrels and forcing 90 the checking liquid, caused to flow into one of the barrels, back again through the channel into the other of the barrels.

4. A door-checking hinge, comprising barrels, a web for the barrels having a channel communicating with the interior of each of the barrels for equalizing the checking liquid in the barrels and channel, an obstructing wall within one of the barrels, an oscillating shaft contacting with the obstructing wall, and forming a substantially liquid-tight contact therewith, a wing on the shaft, and a projecting finger on the wing adapted to open and close the end of the channel on the oscillation of the shaft. 105

5. A door-checking hinge, comprising barrels, a web for the barrels having a channel communicating with the interior of each of the barrels for equalizing the checking liquid in the barrels and channel, an obstructing wall in each of the barrels, an oscillating shaft in each of the barrels, a wing on the shaft, and a projecting finger on the wing adapted to open and close the end of the channel on the oscillation of the shaft, 110 said projecting finger having an opening near the end thereof adapted to register with the end of the channel.

6. A door-checking hinge, comprising barrels, a web for the barrels having a channel communicating with the interior of each of the barrels for equalizing the checking liquid in the barrels and channel, an obstructing wall in each of the barrels, an oscillating shaft in each of the barrels, a wing 120 on the shaft, a projecting finger on the wing adapted to open and close the end of the channel on the oscillation of the shaft, said projecting finger having an opening 125 near the end thereof adapted to register 130

with the end of the channel, and leaves, one for each barrel.

7. A door-checking hinge, comprising barrels, a web for the barrels having a channel communicating with the interior of each of the barrels for equalizing the checking liquid in the barrels and channel, an obstructing wall in each of the barrels, an oscillating shaft in each of the barrels, means on the oscillating shaft for operating the liquid, a collar on the shaft having substantially the same diameter as the interior of the barrel, an enlarged collar seated on the barrel, and leaves, having ears one for each barrel.

8. A door-checking hinge, comprising barrels, a web for the barrels having a channel communicating with the interior of each of the barrels for equalizing the checking liquid in the barrels and channel, an oscillating shaft in each barrel having means thereon for causing the flow of the checking liquid into either of the barrels and forcing the checking liquid, caused to flow into one of the barrels, through the channel into the other of the barrels, and means controlling the flow of the checking liquid through the channel.

9. A door-checking hinge, comprising barrels, a web for the barrels having a channel communicating with the interior of each of the barrels for equalizing the checking liquid in the barrels and channel, an oscillating shaft in each barrel having means thereon for causing the flow of the checking liquid into either of the barrels and forcing the checking liquid, caused to flow into one of the barrels, through the channel into the other of the barrels, and means in the path of the checking liquid in the channel, for controlling the flow of the checking by and through the channel.

10. A door - checking hinge, comprising barrels, a web for the barrels having a channel communicating with the interior of each of the barrels for equalizing the checking liquid in the barrels and channel, an oscillating shaft in each barrel having means thereon for causing the flow of the checking liquid into either of the barrels and forcing the checking liquid, caused to flow into one of the barrels, through the channel into the other of the barrels, and an adjustable plug passing through the web for varying the cross-sectional area of the channel.

11. A door-checking hinge, comprising a web having a channel passing therethrough, a barrel at each end of the web and having its interior in communication with the end of the channel of the web, means for controlling the cross-sectional area of the channel, an oscillating shaft in each barrel having a wing movable therewith and having a projecting finger for opening or closing the

end of the channel, the projecting finger having an opening adapted to be brought into registration with the end of the channel, leaves, one for each barrel, and means connecting each leaf with the oscillating shaft in each barrel.

12. A door-checking hinge, comprising a web having a channel passing therethrough, a barrel at each end of the web and having its interior in communication with the end of the channel of the web, means within the channel for controlling the cross-sectional area of the channel, an oscillating shaft in each barrel having a wing movable therewith and having a projecting finger for opening or closing the end of the channel, the projecting finger having an opening adapted to be brought into registration with the end of the channel, two collars on the oscillating shaft having a diameter substantially equal to the diameter of the interior of the barrel, a packing arranged between the two collars, an enlarged collar on the oscillating shaft seated on the upper part of the barrel, a leaf, for each barrel, ears on the leaves, a vertical rod passing through the ears and engaging the enlarged collar of the oscillating shaft, and rods passing through openings in the ears, through the enlarged collar of the oscillating shaft, and through the vertical rods for locking the leaves to the oscillating shaft.

13. A door - checking hinge, comprising barrels, a connecting member for the barrels having a channel communicating with the interior of each of the barrels for equalizing the checking liquid in the barrels and channel, and leaves supporting the barrels and connecting member.

14. A door - checking hinge, comprising barrels, a connecting member for the barrels having a channel communicating with the interior of each of the barrels for equalizing the checking liquid in the barrels and channel, leaves, means for fastening the connecting member to one of the leaves, and extension brackets on each of said leaves, and a link connecting the ends of said extension brackets.

15. A door - checking hinge, comprising barrels, a connecting member for the barrels having a channel communicating with the interior of each of the barrels for equalizing the checking liquid in the barrels and channel, leaves, means for fastening the connecting member to one of the leaves, and extension brackets on each of said leaves, a link connecting the ends of said extension brackets, and a closing spring for moving the leaves into closing position.

16. A door - checking hinge, comprising barrels, a connecting member for the barrels having a channel communicating with the interior of each of the barrels for equalizing the checking liquid in the barrels and chan-

nel, leaves, means for fastening the connecting member to one of the leaves, and extension brackets on each of said leaves, a link connecting the ends of said extension brackets, the said leaves having each three ears, a barrel interposed between two of said ears, an oscillating shaft in said barrel, means connected with said oscillating shaft for moving the checking liquid into and out of 10 said barrel, a second barrel interposed between one of the two ears and the third ear, spring-holders in said second barrel, a spring for said spring-holders, and a pintle for said ears, spring and spring-holders.

15 17. A door - checking hinge, comprising barrels, a connecting-member for the barrels having a channel communicating with the interior of each of the barrels for equalizing the checking liquid in the barrels and channel, and means in one of the barrels for al-

20 nel, and means in one of the barrels for al-

ternately withdrawing and returning checking liquid from the other barrel.

18. A door - checking hinge, comprising barrels, a connecting member for the barrels having a channel communicating with the 25 interior of each of the barrels for equalizing the checking liquid in the barrels and channel, and means in one barrel for withdrawing checking liquid from the other barrel when the door is opened, and for forcing 30 said checking liquid back to the other barrel when the door is closed.

In testimony, that I claim the foregoing as my invention, I have signed my name in presence of two subscribing witnesses.

EMIL BOMMER.
